UNITED STATES PATENT OFFICE

CHARLES E. WILCOX, OF LONG BEACH, CALIFORNIA

ELEVATOR

Application filed March 28, 1929. Serial No. 350,580.

This invention has to do with a well tool and relates more particularly to an elevator for handling well drilling tools or equipment. It is a general object of the invention to provide a simple, inexpensive, and dependable elevator.

Devices known as elevators are used to handle various tools and equipment during the drilling and operation of wells. Elevators are most commonly used to handle drill pipe and casing. It is of great importance that an elevator of this class be safe and dependable in operation, that it be strong and durable, and that it be simple, convenient, and quick in operation. Most elevators in use depend upon a spring latch to hold them in operating position and they are therefore not altogether dependable or safe. Constructions and arrangements have been proposed in which the load or work being handled is used to hold the parts in operating position, however, these constructions have not been altogether satisfactory as they have been difficult or slow to operate or have involved various latch devices, keys, or other parts making them complicated, delicate, and commercially impractical.

It is a general object of the present invention to provide an elevator which is held closed by the work being handled and which is convenient and quick in operation and free of special latch devices or other parts subject to failure or operating to complicate the tool.

It is another object of the invention to provide an elevator in which the parts are such as to be held in operating position by the work being handled and in which there is also a dependable, effective, and practical latch which operates to hold the parts in operating position regardless of whether there is a load on the tool.

It is a further object of this invention to provide an elevator having parts which lock it in operating position upon a load being applied to the tool and which are automatically released when the load is removed from the tool.

It is another object of the invention to provide an elevator of the general type above referred to adapted to be opened and closed

by a simple swinging or pivotal movement between the main parts or sections.

The various objects and features of the invention will be best and more fully understood from the following detailed description of a typical form and application of the invention, throughout which description reference is had to the accompanying drawings, in which:

Fig. 1 is a side elevation of an elevator embodying the invention showing it open and in position on a pipe ready to be closed. Fig. 2 is a view similar to Fig. 1 showing the elevator closed. Fig. 3 is a plan view of the elevator showing it open, being a view taken as indicated by line 3-3 on Fig. 1. Fig. 4 is a plan view of the elevator showing it closed, being a view taken as indicated by line 4-4 on Fig. 2. Fig. 5 is an enlarged view showing a part of the elevator with the parts in closed position ready for the elevator to be operated to receive a load, being an enlarged view taken substantially as indicated by line 5-5 on Fig. 4. Fig. 6 is a view similar to Fig. 5 showing the elevator operated or in position where it is carrying a load. Fig. 7 is an enlarged detailed sectional view taken through the latch of the elevator, being a view showing the manner in which the latch operates to hold the elevator closed. Fig. 8 is a detailed sectional view taken as indicated by line 8-8 on Fig. 7 showing the parts in position corresponding to that illustrated in Figs. 2 and 5 of the drawings. Fig. 9 is a view similar to Fig. 8 showing the parts in position corresponding to that in Fig. 6. Fig. 10 is an enlarged detailed sectional view taken as indicated by line 10-10 on Fig. 4 showing the parts in position corresponding to that illustrated in Figs. 2, 5 and 8. Fig. 11 is a plan section taken as indicated by line 11-11 on Fig. 5, and Fig. 12 is a view showing the end of the gate section of the elevator.

The construction provided by this invention is applicable, generally, to elevators such as are used in well drilling rigs. For purpose of example, I will describe a well casing elevator and I have illustrated a well casing provided with the usual coupling 11. The 100

elevator is adapted to surround the casing 10 and to be moved upwardly into engagement with the shoulder 12 at the lower end of the coupling to lift the casing through the engagement with the coupling.

5 The elevator provided by the present invention includes, generally, two sections A and B operable to embrace the casing, a connection C between the sections whereby they are free to be operated, that is, opened and closed for casing engagement, and means D for securing or releasably holding the sections in closed or casing engaging position.

10 The invention may be carried out in connection with elevators of various styles or types, however, it is particularly applicable to the side-door type of elevator, and therefore I have illustrated this type of elevator throughout the drawings. In the construction shown the section A, which is the main or body section, is substantially U-shaped in plan configuration. The casing receiving opening that extends into the body from one side is comparatively deep so that the casing is completely received within the body. The inner end portion 13 of the body opening is rounded to conform to the exterior of the casing to be handled by the elevator.

15 The section B is in the nature of a closure or gate adapted to extend between two spaced side portions 14 and 15 of the body. The gate is designed to retain the casing in place within the body section A and is preferably formed so that its inner face 16 is curved to conform to the curvature of the casing as illustrated throughout the drawings.

20 The connection C between the sections A and B, that is, between the body and gate of the elevator, is preferably a pivotal connection joining the sections so that the gate section B can be freely swung horizontally between the open and closed positions illustrated in the drawings and can be moved vertically to engage and release the parts of the sections as hereinafter described.

25 In the form of construction illustrated the connection is made by a pivot pin 17 carried between spaced upper and lower lugs 18 and 19 on one section and extending through a lug 20 on the other section. In the particular arrangement illustrated the spaced lugs 18 and 19 are located on or project from the end part of the side portion 15 of the body section A, while the lug 20 projects from one end which I will term the inner end of the gate, and is located between the lugs 18 and 19. The pivot pin 17 is tightly carried by or between the lugs 18 and 19 and fits the opening 21 through the lug 20 so that the gate can swing freely about the pivot pin and can slide or move vertically on the pivot pin. The vertical height or thickness of the lug 20 is considerably less than the vertical distance between the lugs 18 and 19, thus allow-

30 ing for vertical movement of the gate section B with reference to the body section A.

35 The means D provided for securing or releasably holding the sections A and B in casing engaging position is preferably arranged to connect the free or outer end of the gate section B with the end part of the side portion 14 of the body section A. The means D is preferably a latch means operable to automatically connect the gate and body sections upon the sections being moved to operating positions around the casing as shown in Figs. 2, 4 and 7 of the drawings. I have shown a spring actuated latch 22 carried by one of the sections to cooperatively engage the other section. In the particular arrangement illustrated the latch 22 is pivotally mounted at the outer end of the body portion 14 to engage the free or outer end portion of the gate B. The latch 22 is arranged between spaced lugs 23 and 24 on the outer end of the body portion 14 and is held by a pivot pin 25 extending between these lugs and through the latch. The latch is provided with a shoulder 26 to cooperatively engage a shoulder 27 on the outer end portion of the gate, as clearly illustrated in Fig. 7. The shoulder 27 is formed on the gate by providing a lug or projection 28 on the outer end portion of the gate in position to receive the latch. A spring, for instance, a helical spring 30 is arranged between a suitable part of the body and the latch 22 to normally urge the latch to the closed or operating position.

40 The latch is provided with a suitable part 31 which cooperates with a part of the body portion 14 to limit the amount the latch may be moved under action of the spring 30. Further, the latch is provided with a projecting portion or head 32 which projects beyond the body portion 14 and is shaped and proportioned to form a handle by which the latch can be readily opened. In the preferred arrangement the head portion 32 of the latch 100 is located adjacent a handle 33 provided on the outer end portion of the gate, making the tool simple and convenient to operate.

45 In accordance with my present invention the sections A and B are provided with cooperating parts engaged by vertical movement of the gate with reference to the body so that the gate is positively locked in closed position when the elevator is carrying a load. In the preferred form of the invention there 115 are cooperating parts at both ends of the gate so that the gate is effectively held or locked closed by its engagement with the body as well as by the connection C and the latch means D.

50 In the form of the invention shown means is provided between the sections whereby the gate section B is normally urged upwardly to be in the position illustrated in Figs. 1, 2, 5, 8 and 10 of the drawings in 120

which position the cooperating parts that I have just referred to are disengaged. This means is preferably a spring means, for instance, it may comprise a helical spring 40 carried on the pivot pin 17 between the lugs 19 and 20. In the preferred form of the invention one of the lugs is provided with a socket 41 surrounding the pivot pin 17 to receive the spring 40. This allows for a spring of substantial length and for proper lowering of the gate, as will be hereinafter described.

The locking parts, as I will term the cooperating parts of the sections at the pivotal connection between the gate and body, may include a projection 42 on one of the sections, for instance, on the body section, to extend into a socket 43 formed in the other section, that is, in the gate section. In the case illustrated the projection 42 is in the form of a pin projecting upwardly from the outer portion of the lug 19 while the socket 43 is formed in the lower side of the lug 20. The pin projection 42 and the socket 43 are located so that they are in line or register when the gate is in the closed position and so that the pin projects into the socket to lock the gate against pivotal movement upon the gate being depressed or lowered to the position shown in Figs. 6 and 9 of the drawings.

The cooperating parts provided for locking the outer end of the gate B with the side portion 14 of the body may include a tongue 50 projecting from one of the sections, for instance, from the outer end portion of the gate, and a flange-like projection 51 on the other section, that is, on the outer part of the body portion 14. In the arrangement shown the tongue 50 and flange projection 51 are located below the latch means D, as clearly illustrated through the drawings. The tongue 50 is preferably in the form of a thick or heavy projection on the outer end portion of the gate and is preferably provided with a flat side 52 adapted to engage the end wall 53 of the body portion 14 when the gate is in closed position. The tongue is located on the gate so that it may be passed between the latch carrying lug 24 and the flange projection 51 when the gate B is up, as shown in Figs. 1, 2, 5 and 8 of the drawings. In the preferred arrangement there is just sufficient space between the latch carrying lug 24 and the flange projection 51 to pass the tongue 50. A depression or recess 54 is provided in the upper side of the flange projection 51 to receive the tongue 50 upon the gate section B being depressed or moved downwardly to the position shown in Figs. 6 and 9 of the drawings. The manner in which the tongue 50 is received by the recess 54 is clearly illustrated in Fig. 9 of the drawings. It will be obvious how the recess holds the tongue so that the gate cannot be swung outwardly, or open, when in the down position.

Further, cooperating locking parts may be provided by forming the lug 28 on the outer end of the gate B so that it lowers into a notch or recess 60 in the latch carrying lug 24 when the gate is lowered. The lug 28 is preferably proportioned or made of sufficient vertical extent as to remain in engagement with the latch 22 throughout movement of the gate between the positions referred to. The relation of the lug 28 to the latch will be clearly understood from examination of Figs. 7, 8 and 9 of the drawings.

The gate B is proportioned or related to the body section A so that its upper end or face 70 projects somewhat above the upper end or face 71 of the body when the gate is up, as shown in Figs. 2, 5, 8 and 10 of the drawings.

The gate is thus in position to engage the shoulder 12 of the coupling 11 before the body, causing the gate to move vertically relative to the body so that the locking parts are engaged as the elevator is moved upwardly on the casing 10 to lift the casing through engagement with the coupling. The manner in which the coupling operates to move the gate so that the locking parts are engaged will be apparent from examination of Fig. 6 of the drawings.

Bails for carrying the elevator may be connected to the body A in any suitable manner. In the case illustrated bail ears 72 project from the sides of the body at diametrically opposite points and are provided with openings 74 carrying bails 75. The bails extend upwardly and suspend the elevator from a traveling block, or the like.

In operating the elevator the body is arranged on the casing 10, as shown in Figs. 1 and 3 of the drawings, whereupon the gate section B is swung closed so that the latch means D releasably secures the sections together in operating or casing engaging position. The elevator is then moved upwardly during which movement the gate section is stopped by the collar before the body section reaches the collar, causing the gate section and the body section to move relative to each other vertically so that the locking parts on the two sections are engaged. It will be obvious that the parts will remain in this locked position so long as there is sufficient load on the elevator to hold the gate down against the resistance of the spring 40. When it is desired to release the elevator, it is lowered on the casing until it is free of the coupling. When in this position, the spring 40 holds the gate up so that the locking parts on the sections are disengaged. The operator then actuates the latch, completely freeing the sections so that the gate can be swung open allowing the elevator to be disengaged from the pipe.

Having described only a typical, preferred form of the invention, I do not wish to limit

myself to the specific details set forth, but wish to reserve to myself any changes or variations that may appear to those skilled in the art or fall within the scope of the following claims.

5. Having described my invention, I claim:
1. An elevator including, two pivotally connected sections adapted to engage around a casing, a latch for holding the sections in casing engaging position, the sections being shiftable relative to each other when in casing engaging position and having cooperating locking parts engageable by shifting of the sections, and means yieldingly holding the sections in position where said parts are disengaged.
  2. An elevator including, two pivotally connected sections adapted to engage around a casing, a spring latch for automatically connecting and holding the sections in casing engaging position, the sections being shiftable relative to each other when in casing engaging position and having cooperating locking parts engageable by shifting of the sections, and means yieldingly holding the sections in position where said parts are disengaged.
  3. An elevator including, two pivotally connected sections adapted to engage around a casing, a latch for holding the sections in casing engaging position, the sections being shiftable relative to each other parallel with the casing when in casing engaging position and having cooperating locking parts engageable by shifting of the sections, and means yieldingly holding the sections in position where said parts are disengaged.
  4. An elevator including, two pivotally connected sections adapted to engage around a casing, a latch for holding the sections in casing engaging position, the sections being shiftable relative to each other when latched in casing engaging position and having cooperating locking parts engageable by shifting of the sections, and means yieldingly holding the sections in position where said parts are disengaged.
  5. An elevator including, two pivotally connected sections adapted to engage around a casing, a latch for holding the sections in casing engaging position, the sections being shiftable relative to each other when in casing engaging position and having cooperating locking parts engageable by shifting of the sections, and spring means yieldingly holding the sections in position where said parts are disengaged.
  6. An elevator including, two pivotally connected sections adapted to engage around a casing, a latch for holding the sections in casing engaging position, the sections being shiftable relative to each other when in casing engaging position and having cooperating locking parts at their adjoining portions engageable by shifting of the sections, and

means yieldingly holding the sections in position where said parts are disengaged.

7. An elevator including two pivotally connected sections adapted to engage around a casing, a spring latch for automatically connecting the sections to hold them in casing engaging position, the sections being shiftable relative to each other parallel with the casing when in casing engaging position and having cooperating locking parts at their adjoining portions engageable by shifting of the sections, and spring means yieldingly holding the sections in position where the said parts are disengaged.

8. An elevator including, two pivotally connected sections adapted to engage around a casing, a latch for holding the sections in casing engaging position, the sections being shiftable relative to each other when in casing engaging position and having cooperating locking parts engageable by shifting of the sections, and means at the pivotal connection between the sections yieldingly holding the sections in position where said parts are disengaged.

9. An elevator including, a body, a gate, a connection between the body and gate whereby the gate can swing and move vertically relative to the body, a latch for holding the gate in closed position, cooperating parts on the body and gate engaging to lock the gate against opening when the gate is closed and in a down position, and means normally yieldingly holding the gate up so that said parts are disengaged.

10. An elevator including, a body, a gate, a connection between the body and gate whereby the gate can swing and move vertically relative to the body, a horizontally moving latch for holding the gate in closed position, cooperating parts on the body and gate engaging to lock the gate against opening when the gate is closed and in a down position, and means normally yieldingly holding the gate up so that said parts are disengaged.

11. An elevator including, a body, a gate, a connection between the body and gate whereby the gate can swing and move vertically relative to the body, a latch for holding the gate in closed position, cooperating parts on the body and gate engaging to lock the gate against opening when the gate is closed and in a down position, and means at the connection between the body and gate normally yieldingly holding the gate up so that said parts are disengaged.

12. An elevator including, a body, a gate, a connection between the body and gate whereby the gate can swing and move vertically relative to the body, a latch for holding the gate closed around a casing, cooperating parts on the body and gate engaging to lock the gate against opening when the gate is closed and in a down position, and

means normally yieldingly holding the gate up so that said parts are disengaged, the gate and body being related so that the gate is moved down relative to the body when the elevator bears the load of the casing.

13. An elevator including, a body, a gate, a connection between the body and gate whereby the gate can swing and move vertically relative to the body, a latch for holding the gate closed around a casing, cooperating parts on the body and gate engaging to lock the gate against opening when the gate is closed and in a down position, and means normally yieldingly holding the gate up so that said parts are disengaged, the gate and body being related so that the gate is down relative to the body only when the elevator bears the load of the casing.

14. An elevator including, a body, a gate, a connection between the body and gate whereby the gate can swing and move vertically relative to the body, a latch for holding the gate in closed position, cooperating parts on the body and gate engaging to lock the gate against opening when the gate is closed and in a down position, and means normally yieldingly holding the gate up so that said parts are disengaged, there being cooperating parts at the inner and outer ends of the gate.

15. An elevator including, a body, a gate, a connection between the body and gate whereby the gate can swing and move vertically relative to the body, a latch for holding the gate in closed position, cooperating parts on the body and gate engaging to lock the gate against opening when the gate is closed and in a down position, and means normally yieldingly holding the gate up so that said parts are disengaged, the latch operating to hold the gate closed during vertical movement between the body and gate when the gate is in closed position.

16. An elevator including, a body, a gate, a connection between the body and gate whereby the gate can swing and move vertically relative to the body, a latch for holding the gate in closed position, a tongue on the gate adapted to lower into a recess in the body when the gate is in closed position, and means normally yieldingly holding the gate in an up position relative to the body.

17. An elevator including, a body, a gate, a connection between the body and gate whereby the gate can swing and move vertically relative to the body, a latch for holding the gate in closed position, a tongue on the outer end portion of the gate adapted to lower into a recess in the body when the gate is in closed position, and means normally yieldingly holding the gate in an up position relative to the body.

18. An elevator including, a body, a gate, a connection between the body and gate whereby the gate can swing and move ver-

tically relative to the body, a latch for holding the gate in closed position, a tongue on the outer end portion of the gate adapted to lower into a recess in the body when the gate is in closed position, and a spring on the said connection between the body and gate normally yieldingly holding the gate in an up position relative to the body.

In witness that I claim the foregoing I have hereunto subscribed my name this 18th day of March, 1929.

CHARLES E. WILCOX.
